SIGNALING DEVICE

John M. Aufiero, Brooklyn, N. Y., assignor to
E. A. Laboratories, Inc., Brooklyn, N. Y., a cor-
poration of New York

Application October 3, 1934, Serial No. 746,636

5 Claims. (Cl. 116—138)

This invention relates to a warning signal or horn of the vacuum type.

It is an object of the invention to provide a functionally and structurally improved signal by means of which an extremely desirable type of warning tone or sound may be produced.

A further object of the invention is that of furnishing an apparatus of this nature in which a double note effect will be achieved in an im-
10 proved manner.

A further object is that of furnishing an apparatus which will include relatively few parts, each individually simple and rugged in construction and capable of manufacture by quantity produc-
15 tion methods, these parts being extremely compact and capable of assemblage by relatively un-
skilled labor, and, when assembled, permitting of rapid adjustment—should adjustment be de-
sired—and operating over long periods of time
with freedom from all difficulties.

20 With these and other objects in mind, reference is had to the attached sheet of drawings il-
lustrating one preferred form of the invention,
and in which—

25 Fig. 1 is a plan view of a sounding device or unit constructed in accordance with the present invention;

Fig. 2 is a rear view thereof with certain of the parts removed to disclose the underlying con-
struction; and

30 Fig. 3 is a transverse sectional view taken along the lines 3—3 and in the direction of the arrows as indicated in Fig. 2.

While the teachings of the present invention are
35 not necessarily restricted to a multitone sounding device, it is one of the primary features of this invention to produce a desirable device of this character, and in which the parts may largely be manufactured by die casting or other suit-
able quantity production methods.

40 Thus the numerals 5 and 6 indicate trumpet portions which have a common base plate 7 and are connected by a brace portion 8. All of these parts preferably form integrally connected portions which are produced simultaneously. As shown in dotted lines in Fig. 2, the base 7 has at a point intermediate the axes of trumpets 5 and 6 a notch or depressed portion, the purpose of which will be hereinafter brought out.

45 Positioned to the rear of the base 7 is a casing 9 which may also be die cast. This casing preferably includes a side wall of an area equal to the base 7 and has a pair of similar internal flange or partition portions 10, each of which has an opening 11 in axial alignment with one of the

trumpet portions when the casing is applied to the base 7. Thus, there is provided to the rear of each partition 10 a chamber 12. The casing 9 is also formed with a tubular portion 13 which lies substantially within the area of the casing base and the notched portion heretofore described as being shown in dotted lines in Fig. 2. The tubular portion may be divided into separate compartments by means of a flange 14, and rearwardly of this flange access to the interior of the tube is afforded by means of an angularly extending nipple 15, which may be internally threaded. The openings 16 may also be formed at the time of manufacture of the casing portion 9, and these latter openings communicate respectively with the interior of the bore of the tube 13 and the two chambers 12.

The rear face of the casing is closed as, for example, by a pair of separate caps 17, and with a view to maintaining the parts in assembled condition, bolts 18 are preferably employed and extend through openings in the caps 17 through bored bosses or columns 19 formed integrally with the casing 9 and into screw-threaded re-
cesses or openings in the base 7.

25 It will be observed that the partition members 10 have each chamber preferably terminating in a plane inwardly of the rear edge of the casing 9. In this manner seats are provided for dia-
phragms 20, so that the latter lie within the area 30 of the casing 9. Also the caps 17 may have their edge portions reduced as at 21, so that they in turn may extend into this space and, as shown in Fig. 3, provide what in effect is an air-tight seal.

35 The openings of the partition members 10 are preferably defined by forwardly extending flanges 22, which flanges have an area substantially less than the base portions or bores 23 of the trump-
ets 5 and 6. In this manner there are provided 40 what might be termed valve seats which are en-
gaged by valves, preferably including bodies each formed of a pair of superposed disks 24 of differ-
ent diameters and of which the outermost is 45 preferably the smallest, to thus somewhat rigidify the innermost, which forms the valve proper. The mounting of these valves is secured by hav-
ing them centrally apertured and disposed upon a common stem 25, which may have its outer 50 end headed as at 26 to prevent accidental de-
tachment of the parts. Washers 27 may be dis-
posed above and below the valve bodies not alone 55 to prevent any possibility of chattering, but also to maintain the central portions of the valve bodies substantially rigid. The diaphragms 20

are each formed with a central opening preferably mounting nuts 28 with which washers 29 and resonators 30 may be associated. The shanks of the stems 25 are preferably each screw-threaded as at 31 so as to engage the threads of the nut, and a lock nut 32 may, in each instance, be employed to lock the stems against movement with respect to the diaphragms.

In this manner an adjustment is provided in 10 that each of the diaphragms embodies a certain inherent resiliency which, with the parts set up in the manner afore noted, serves to maintain the valves normally in seated condition upon their seats. Each of the caps 17 preferably has applied to it a removable casing or closure element 33' which, upon removal, permits access to the nut 32. Consequently, an operator may adjust the degree of intimacy with which the respective valves normally engage their seats.

20 Disposed within the tube 13 is a valve member which again is preferably formed of a single piece of stock, and which may include a plug body 33 having a reduced end portion 34, suitable for attachment to an actuator, and a forward portion 35 encircled by a spring 36 having one of its ends coupled to that end portion and its opposite end bearing against the flange 14 so as to normally maintain the valve in seated condition. In other words, a flow of air through 30 the passages 16 and nipple 15 is normally precluded.

With the parts positioned in the manner afore noted, it will, of course, be understood that if the nipple 15 is connected by means of a tube 37 with a source of vacuum, and if an actuator 38 is operated to pull the body 33 rearwardly, such source of vacuum will cause a lowering of the pressure within each of the chambers 12. Due to the fact that the area of the diaphragms 40 20 is substantially greater than the area of the valve bodies, these diaphragms will be deflected inwardly, resulting in an unseating of the valves. With a continued opening of the control valve portion 33, the valves 24 will now vibrate at 45 acoustical frequencies incident to the inrush of air through the trumpet portions 5 and 6, through the openings 11, passages 16, tube 13, and nipple 15. As has been shown, the trumpet portions are preferably of different lengths so that 50 they will have different natural frequencies, and with this in mind, tension exerted upon the two valves or disk assemblies is proportioned so that the latter will tend to vibrate at frequencies harmonious to the natural frequencies of the trumpet portion. In this manner an extremely pleasing and harmonious signal results, which is nevertheless penetrating and far reaching, and serves adequately to produce a warning notice which 55 is extremely effective.

60 Aside from the parts associated with the diaphragm it will be observed that merely three die castings or equivalent elements are involved. Insofar as the diaphragm assemblies are concerned, they may also be manufactured by quantity 65 production methods, and the assembly offers no serious complications. Therefore, it will be obvious that a satisfactory warning signal may be produced to sell at an extremely nominal figure without, however, sacrificing any of the characteristics which should be embodied in a warning 70 signal.

In conclusion it will be appreciated that while, for the sake of economy, it is preferred to produce a warning signal in the manner afore outlined, it is not necessary to resort to die cast-

ing operations. Additionally, a unit of this nature might embody any desired number of sounding assemblies instead of the double assembly which has been illustrated. However, again for most purposes, it is preferred to employ a double rather than a single assembly, and it is found that the addition of such assemblies does not add materially to the effectiveness of the warning signal. 5

Thus, among others, the several objects of the 10 invention as specifically afore noted are achieved. It will be understood, however, that numerous changes in construction and rearrangement of the parts might be resorted to without departing from the spirit of the invention as defined 15 by the appended claims.

Having thus described the invention, what is claimed is:

1. A sounding device including a casing, a partition member integral therewith, a tube also 20 integral with said casing, said tube being formed with openings through its side walls, one of said openings extending through said partition member, a valve disposed within said tube and controlling the flow of air through said openings, 25 and a disk movably associated with said partition member and to vibrate at acoustical frequencies.

2. A sounding device including, in combination, 30 a casing, a pair of partition members disposed within said casing, each of said partition members being formed with an opening, a tube disposed substantially intermediate the partition members and integral with the latter and said casing, said tube being formed with a plurality of openings, two of which extend respectively 35 through the partition members and to the casing space to the rear thereof, a valve disposed within said tube and controlling the flow of air through said openings, disks associated one with each of the first named partition openings, and means 40 responsive to the flow of air through said openings for vibrating said disks at acoustical frequencies.

3. A sounding device including, in combination, 45 a casing, a pair of partition members disposed within said casing, each of said partition members being formed with an opening, a tube disposed substantially intermediate the partition members and integral with the latter and said casing, said tube being formed with a plurality of 50 openings, two of which extend respectively through the partition members and through the casing space to the rear thereof, a valve disposed within said tube and controlling the flow of air through said openings, disks associated one with each of the first named partition openings, means 55 responsive to the flow of air through said openings for vibrating said disks at acoustical frequencies, and boss elements also forming integral parts of said casing and disposed in line with the peripheral portion of said partition members, said boss members accommodating securing elements to attach parts to said casing.

4. A sounding device including a casing, a partition member integral therewith, a tube also 65 integral with said casing, said tube being formed with openings through its side walls, one of said openings communicating with the space to the rear of said partition member, said member being also formed with an opening, a valve disposed 70 within said tube to permit of a flow of fluid through its body from one of its openings to the other of the same, a diaphragm to the rear of said partition member, a valve beyond said partition member and to control the flow of fluid 75

through the opening thereof, and means connecting said diaphragm with said latter valve.

5. A horn including, in combination, a pair of trumpet portions, a base common to the same and being formed with a notch, a casing secured to said base and bridging said notch, a tube associated with said casing and disposed to extend within said notch, a control member within said tube, means vibrating at acoustical frequencies

within said base for causing sound waves to be projected by said trumpet portions, said tube being in communication with a source of suction and being formed with openings communicating with said base whereby when said control member is moved within said tube the means within said base will be caused to vibrate. 5
